US00D961853S

(12) **United States Design Patent** (10) Patent No.: **US D961,853 S**
 Van Roosmalen et al. (45) Date of Patent: ** Aug. 23, 2022

(54) **COMBINED HANDLE AND DISPLAY FOR SHAVER**

(71) Applicant: **KONINKLIJKE PHILIPS N.V.**, Eindhoven (NL)

(72) Inventors: **Jos Van Roosmalen**, Amsterdam (NL); **Frank Verbrugge**, Rosmalen (NL); **Jens Andersson**, Amsterdam (NL); **Roel Krooshof**, Bilthoven (NL); **Simon Van Anken**, Amsterdam (NL); **Peter Gal**, Amsterdam (NL); **Lieven Adriaenssen**, Vilvoorde (BE); **Roshan Hakkim**, Amsterdam (NL); **Mingshuo Zhang**, Amstelveen (NL)

(73) Assignee: **KONINKLIJKE PHILIPS N.V.**, Eindhoven (NL)

(**) Term: **15 Years**

(21) Appl. No.: **29/725,800**

(22) Filed: **Feb. 27, 2020**

(51) LOC (13) Cl. **28-03**

(52) U.S. Cl.

USPC **D28/54**; D28/50

(58) **Field of Classification Search**

USPC D28/49-52, 54
CPC B26B 19/384-3886; B26B 19/388; B26B 19/14-18
